UNITED STATES PATENT OFFICE.

WALTER SCHAFFER, OF BERLIN, GERMANY, ASSIGNOR TO GESELLSCHAFT FÜR DRÄHTLOSE TELEGRAPHIE M. B. H., OF BERLIN, GERMANY, A CORPORATION OF GERMANY.

OSCILLATOR GENERATOR.

Application filed July 15, 1925, Serial No. 43,700, and in Germany July 25, 1924.

Owing to various causes, it has heretofore been found difficult to produce very high frequency oscillations by means of transmitting apparatus employing vacuum tubes. Aside from the fact that the effect of internal capacities is increased as the tubes are made of greater power, another difficulty arises in maintaining generated oscillations evenly at the desired constant frequency. The cause underlying this difficulty of obtaining the necessary constancy of frequency is the fact that when primarily and directly producing short waves, the capacitance of the circuit which determines the frequency must be made extremely low. When variations of the position and dimensions of the antenna occur, or very small changes in capacitance are caused, such as by a person approaching the apparatus, or by the movement of conductive bodies in the neighborhood of the apparatus, the effect of small percentage changes of capacitance which govern the frequency and the length of wave assumes relatively large proportions.

An object of the present invention is therefore to obviate the difficulties above referred to so that the effects thereof are diminished at the outset. This is accomplished by first producing a wave of greater length or of low frequency instead of a short wave of high frequency, and then from the anode circuit of the generator tube which produces the primary long wave oscillations there are obtained harmonic waves which are modulated according to the modulation in said primary tube. In the generation of short waves produced by harmonics of a longer wave, as here proposed, the wave length is dependant upon the use of a much larger condenser, in consequence of which capacitative influences, regardless of their nature or source, react primarily upon the fundamental wave, and consequently the effect on the harmonics will be considerably less.

The harmonic waves thus obtained can be supplied directly to the aerial from which they are to be radiated, or to any other kind of utilization, or transfer, or amplification circuit.

As an example of various arrangements

to produce the above results reference may be had to the accompanying drawing forming a part of this specification, in which

Fig. 1 is a diagrammatic view illustrating the general principle of the invention; 55

Fig. 2 is a similar diagrammatic view illustrating a modified form thereof; and

Fig. 3 is a similar diagrammatic view illustrating another modified form of the invention. 60

Referring to the drawings, the numeral 1 indicates the primary generator tube which is connected with an oscillating circuit 2 which may be tuned to a wave length, for example, of 500 meters. In the anode or plate circuit of the tube 1 is connected the oscillatory circuit 3 which may be tuned, for example, to the tenth harmonic, that is to say, a 50 meter wave length. The anode circuit is coupled to the oscillatory circuit 3, as indicated in said Fig. 1, it being assumed, as before pointed out, that the alternating current in the anode circuit is not truly sinusoidal but has been distorted or modulated in shape. This modulation takes place in 75 the normal generation of oscillations produced by means of tubes as soon as the oscillations commence, and are active only on the straight-line portion of the characteristic curve of the tube. The modulation can be further promoted by use of the circuit 3 which is placed in the anode or plate circuit of the tube 1 and tuned to the higher harmonics. This may be further promoted by the aid of auxiliary means, such as by a relatively high negative direct current potential applied to the grid circuit. The energy of the high frequency current thus obtained is, generally speaking, but a comparatively small fraction of the energy which the primary 80 tube is capable of producing, because part of this energy is used up in the oscillatory circuit 2. It will be apparent that in coupling the aerial circuit with the oscillatory circuit 3, the coils may be so arranged and the capacitance so adjusted as to produce the optimum coupling. If increased power is desired, it will be necessary to amplify the harmonics obtained, as above set forth. This can be accomplished most simply by conducting the 85

current of the harmonic oscillations to a high frequency amplifying tube, the output of which is applied to the aerial circuit.

Referring now to Fig. 2, the arrangement therein illustrated is one in which the high frequency oscillations pass through and are amplified in the same tube in which the oscillations of low frequency are generated. The numeral 4 indicates the generator tube and 5 the main oscillatory circuit for the low frequency oscillations. 6 is the oscillatory circuit from which the harmonic oscillations are obtained, this circuit being coupled with the antenna circuit as indicated at 8. From both the high frequency oscillatory circuit and the low frequency circuit, the energy is brought back to the grid of the generating tube through the regenerative couplings indicated at 7 and a coupling with the oscillatory circuit 5, so that the high and low frequency oscillations are amplified and the former thus supplied to the oscillatory circuit 6 from which point they are transmitted to the antenna.

In Fig. 3 an arrangement is illustrated in which the tube 9 is the main generator for the low frequency oscillations which are supplied to the oscillatory circuit 10, in which the low frequency oscillations take place. The high frequency oscillatory circuit is indicated at 11 and is coupled at 12 with the high frequency amplifying tube 13, the output of which supplies the oscillatory circuit 14 with high frequency amplified oscillations. This circuit is coupled with the antenna circuit through a variable coupling as indicated at 16. The oscillatory circuit 14 is also coupled as indicated at 15 with the grid of the main generating tube 9, which circuit is also coupled with the low frequency oscillatory circuit 10 as indicated at 17. A second stage of amplification is thereby produced and the energy thus amplified is then conducted by way of the circuit 11, coupling 12, tube 13 and oscillatory circuit 15 to the antenna circuit 16.

Having thus described these forms of my invention what I claim and desire to protect by Letters Patent is:

1. Apparatus for the generation and radiation of short electric waves of constant frequency comprising, a main generating tube, a parallel resonant oscillatory circuit of comparatively low frequency connected therewith the anode current in which is modulated according to the desired signals to be transmitted, a second parallel resonant oscillatory circuit connected directly in series with the low frequency oscillation circuit of said tube and tuned to a harmonic of the oscillations produced in the first named oscillatory circuit, an antenna circuit and means for coupling said harmonic oscillatory circuit with the antenna circuit.

2. Apparatus for the generation and radiation of short electric waves of constant fre-

quency comprising, a main generating tube, an oscillatory circuit of comparatively low frequency coupled therewith the anode current in which is modulated according to the desired signals to be transmitted, a second oscillatory circuit connected with said tube and tuned to a harmonic of the oscillations produced in the first named oscillatory circuit, means for coupling said low frequency oscillatory circuit with said tube regeneratively, whereby the low frequency oscillations are self generated, an antenna circuit, and means for coupling said harmonic oscillatory circuit with the antenna circuit.

3. Apparatus for the generation and radiation of short electric waves of constant frequency comprising, a main generating tube, an oscillatory circuit of comparatively low frequency connected therewith the anode current in which is modulated according to the desired signals to be transmitted, a second oscillatory circuit connected with said tube and tuned to a harmonic of the oscillations produced in the first named oscillatory circuit, means for regeneratively coupling said low frequency oscillatory circuit tube to generate low frequency oscillations, means to regeneratively couple the harmonic oscillatory circuit to amplify the harmonic, an antenna circuit, and means for coupling said harmonic oscillatory circuit with the antenna circuit.

4. Apparatus for the generation and radiation of short electric waves of constant frequency comprising, a main generating tube, an oscillatory circuit of comparatively low frequency connected therewith the anode current in which is modulated according to the desired signals to be transmitted, a second oscillatory circuit connected with said tube and tuned to a harmonic of the oscillations produced in the first named oscillatory circuit, a tube for amplifying said harmonic oscillations, a third oscillatory circuit connected with said amplifying tube, means for coupling said third circuit with said low frequency oscillation circuit and with the grid of said main generating tube, an antenna circuit, and means for coupling said third oscillatory circuit with the antenna circuit.

5. A tube generator for the production of short waves at constant frequency, comprising a tube oscillator for generating a longer wave, a parallel resonant circuit tuned to a harmonic frequency connected in series with the anode circuit of said tube, and means to utilize the higher frequency.

6. A tube transmitter according to claim 5, in which the harmonic frequency taken from the anode circuit is fed back to the generating tube for the purpose of amplifying the wave of harmonic frequency.

7. A tube transmitter according to claim 5 having a separate amplifier tube to which the harmonic frequency taken from the anode circuit is first fed, and a feed-back connection

whereby the amplified harmonic frequency is re-impressed upon the grid of the generator tube.

8. A tube transmitter for the production of short waves at constant frequency comprising a vacuum tube oscillator for generating a longer wave, a circuit resonant to a desired harmonic of said wave coupled to the anode

circuit of the oscillator tube, and means coupling said resonant circuit to the grid circuit 10 of the oscillator in order to amplify the desired harmonic.

Signed at Berlin, Germany, this 27th day of June, 1925.

WALTER SCHAFFER.
